UNITED STATES PATENT OFFICE

2,056,190

CONCENTRATOR

Enos R. Horton, Denver, Colo.

Application December 30, 1932, Serial No. 649,505

7 Claims. (Cl. 209—44)

This invention relates to concentrators for the extraction of values from metalliferous substances, either in the form of finely divided ores or placer deposits. The invention is particularly adapted for the last-mentioned purpose since it is based, in its operation, upon the principle of the well-known hand-operated "gold pan" which for many years has been accepted as providing the best method of small scale placer gold recovery.

It is an object of the invention to provide a simple mechanically operated apparatus which, in a succession of steps, will effect a clean separation of gold from dirt in auriferous deposits.

Another object is to provide apparatus of this character, operating on the before-mentioned "gold pan" principle, which is of sufficient capacity to be profitable, especially on low grade gold deposits, and further objects reside in details of construction and a novel arrangement and combination of parts as will be fully described in the course of the following description.

In the accompanying drawing, in the several views of which like parts are similarly designated,

Figure 1 is a partially broken plan view of the apparatus.

Figure 2, a sectional and partially broken side elevation of the same,

Figure 3, a section taken on the line 3—3 of Figure 2,

Figure 4, an enlarged fragmentary section of the element of the apparatus in which the material is treated for the extraction of its auriferous constituents, and

Figure 5 is an enlarged fragmentary section, showing the construction of one of the sections of which the element is composed.

Referring further to the drawing, the reference numeral 5 designates a suitable support, preferably in the form of a frame having at one end a step-bearing 6 for the support of the gold-saving element of the apparatus. This element is composed of a number of pan-shaped sections nested one above another for the treatment of the material in successive steps.

The upper section or pan 7 consists of a preferably cylindrical wall supporting two screens 8 and 9 of different meshes, one above the other. The screens slant rearwardly and the upper screen is of larger mesh than the lower one. The upper portion of the pan is shaped to provide a hopper 10, into which the material is fed either by means of shovels or by a feed-belt or other suitable device. Beneath a lip 12 at the rearward side of the hopper is a perforated water pipe 13, for the provision of a wash water in streams directed to the forward side of the pan. These streams form a curtain of water thru which all the material discharging from the hopper, is passed. At the side of the section opposite to

the hopper, is a spout 14 to discharge the oversizes of both screens, outside the pan. The next following section, 15, is composed of a cylindrical wall made of copper and mercury-coated for the amalgamation of fine or flour gold in the material.

The section receives upon its bottom 16, the undersize discharged through the lower screen 9 of the upper section, and it has at its rearward side an outlet 17 for the passage of the material to the next lower section 18.

This next lower section and the lowermost section 19 each consist of a pan having a solid bottom 20 or 21, and upon said bottom a covering 22 or 23 of rubber matting held in place by a wire screen 24 or 25.

The outlet 17 of the amalgamating-pan 15 is connected with an inlet opening 26 in the wall of the section 18, by means of a passage 27 at the forward side of the element. The section 15 has opposite to its inlet 26 an outlet 28 which is connected with an inlet 29 in the wall of the lowermost section 19 by a passage 30. Opposite to the inlet of the lowermost section is a spout 31 for the discharge of tailings from the element. At the bottom of the lowermost section is a pin 31^a and a surrounding ball race 32 for the rotary support of the element on the step-bearing 6 of the frame 5. A ball bearing 33 between the ball race and the bearing is provided for the usual purpose.

The several pan-shaped sections of the concentrating element are nested one upon another and they are clamped together by means of screw-rods 34 pivoted at 37 on spider arms 36 beneath the bottom of the lowermost section, and engaging in slotted lugs 35 on the wall of the uppermost section.

Wing nuts 38 on the threaded ends of the rods engage with the lugs to fasten the sections together. It will be apparent that the several sections thus united may operate as a single unit by movement about its vertical axis.

In the operation of the apparatus, a rotary reciprocating motion is imparted to the unit by means of a shaft 39 mounted in bearings 40 on the frame. The shaft receives its movement from a conveniently located engine by means of a pulley 41, and it carries at its end adjacent the element, a crank-wheel 42 having one or more eccentric openings 43. Into this opening projects a wrist pin 44 on a yoke 45, the legs of which are at their extremities pivotally connected with saddles 46 below the lowermost section of the element.

Rotation of the crank shaft is by these means converted into a rotary reciprocating movement of the unit, closely resembling the movement manually imparted by placer-miners to the hand-pan commonly used in "panning" placer deposits.

Rapid rotation of the crank wheel and the short component stroke induced thereby, impart a vibratory motion of considerable intensity to the unit.

5 The material deposited in the hopper 10 of the nest of pans, is washed toward the upper side of the upper screen by water ejected through the perforations of the pipe 13.

The shaking or vibratory motion of the unit 10 causes the finer particles to pass through the meshes of the coarse screen 8 onto the lower and finer screen 9, while the coarsest particles are discharged through the spout 14. By the same movement, the material is again separated into 15 fines passing through the lower screen, and an oversize discharged through the same spout.

The material passing through the finer screen, falls into the first concentrator pan which amalgamates the gold in the material, principally the 20 finer sizes.

The shaking motion of the unit allows the screened products to come in close contact with the amalgam-covered surface of the pan, and the material that is not amalgamated in this 25 pan flows by gravity to the next concentrating pan and thence to the lowermost concentrating pan. The rubber matting in these pans saves the heavy gold in the material, due to the tendency of the gold to settle in the recesses above 30 the rubber mattings. The wire screens give a swirling action to the mass of material, thereby aiding in the recovery of the gold.

The concentrating pans 15, 18, and 19 recover in successive steps substantially all the gold contained in the material, and the worthless gangue 35 is discharged from the unit through the spout 31.

As indicated by the arrows in Figure 4, the material and the wash water pass through the concentrating pans in a zig-zag course, thereby 40 covering the entire surfaces of the pans. The nest of pans may be slightly tilted by the use of a shim or otherwise, thereby still further simulating the motion imparted to the hand-operated gold pan, and by forming the eccentric holes of 45 the crank-wheel 42 at different distances from its center of rotation, the shaking or rotary reciprocating motion of the nest of pans may be varied according to the requirement of the material under treatment.

50 Owing to the simple method of fastening the pans together, they are easily disconnected and separately removed for cleaning purposes, it being understood that the passages 27 and 30 are rigidly connected with only one of the pans as 55 clearly shown in Figure 4 of the drawing.

What I claim and desire to secure by Letters Patent is:

1. A concentrator comprising a unit mounted for rotary reciprocation about a vertical axis, a 60 crank wheel mounted for rotation about a horizontal axis in a plane transverse to its said axis and parallel to the axis of rotation of the concentrator unit, and a forked rod connecting the crank-wheel with the unit at two radially spaced 65 points to transmit the movement of the crank-wheel into a vibratory movement of the unit.

2. A concentrator comprising a unit mounted for rotary reciprocation about a vertical axis, a 70 crank-wheel mounted for rotation about a horizontal axis in a plane transverse to its said axis and parallel to the axis of rotation of the concentrator unit, a yoke connecting the crank-wheel

with the unit at separated points to transmit the movement of the crank-wheel into a vibratory movement of the unit.

3. A concentrator comprising a unit mounted for rotary reciprocation about a vertical axis, a 5 crank-wheel mounted for rotation about a horizontal axis in a plane transverse to its said axis and parallel to the axis of rotation of the concentrator unit, having an eccentric opening and a rod connecting the crank-wheel with the unit at two angularly spaced points and having a wrist pin extending loosely thru the openings in the crank wheel.

4. In a concentrator having a circular screen, a substantially semi-circular hopper located over 15 the screen, and a water supply pipe extending along the chord side of the hopper, the pipe having a series of perforations on the side facing the curved side of the hopper whereby a plurality of fine water streams will be projected 20 across the hopper.

5. A concentrator comprising a frame mounted for oscillation, a yoke having its two ends pivotally attached to the frame for oscillation about pivots that extend at right angles to the axis of oscillation, the yoke having a wrist pin, a shaft mounted to rotate on an axis perpendicular to the axis of oscillation and a crank wheel carried by the shaft, the crank wheel having an eccentrically located opening for the reception of the 30 wrist pin whereby when the crank wheel is rotated the frame will be oscillated.

6. A concentrator comprising a plurality of concentrating pans placed one above another in nested arrangement, the lower pan supporting all 35 above it, for the successive treatment of material fed onto the uppermost pan, the nested pans having flat horizontal bottoms and being mounted for rotary reciprocation about a vertical axis and the pans, each of the upper pans having 40 overflow means connected to the next lower pan, the overflow means of each pan being diametrically opposite the corresponding overflow means of adjacent pans, the level of the overflow means of each pan being above the bottom thereof, the 45 lowermost pan having an outlet at a point diametrically opposite to the point which connects with the pan immediately above the same, whereby the material must follow a zig-zag course along the entire working surfaces of the 50 pans in its passage from the upper pan to the outlet.

7. A concentrator comprising a plurality of concentrating pans placed one above another in nested arrangement, the lower pan supporting 55 all above it, for the successive treatment of material fed onto the uppermost pan, the nested pans having flat horizontal bottoms and being mounted for rotary reciprocation about a vertical axis, passages connecting an outlet from 60 each upper pan with an inlet to the next lower pan, the passages being at diametrically opposite points of the pans and located above the bottoms of the pans, the lowermost pan having an outlet at a point diametrically opposite the 65 passage which connects with the pan immediately above the same, whereby the material must follow a zig-zag course along the entire working surfaces of the pans in its passage from the upper pan to the outlet, and clamping means for 70 holding the pans in assembled relation.
